United States Patent Office

Des. 180,857
Patented Aug. 27, 1957

180,857

LATEX FABRIC

Paul E. Ambrose, Dover, Del., assignor to International Latex Corporation, Dover, Del., a corporation of Delaware

Application February 20, 1956, Serial No. 40,233

Term of patent 14 years

(Cl. D92—1)

The figure is a plan view of a latex fabric showing my new design.

I claim:

The ornamental design for a latex fabric as shown.

References Cited in the file of this patent

UNITED STATES PATENTS

D. 108,993 Barth _____ Mar. 22, 1938